UNITED STATES PATENT OFFICE.

IRVING F. KLEINFIELD, OF NEW YORK, N. Y.

DESIGN FOR A BOWL.

Application filed October 27, 1921. Serial No. 510,969. Term of patent 3½ years.

To all whom it may concern:

Be it known that I, IRVING F. KLEINFIELD, a citizen of the United States, residing at No. 1092 President Street, in the county of Kings, city of New York, State of New York, have made a certain new, original, and ornamental Design for Bowls, of which the following is a specification, reference being had to the accompanying drawing, forming part thereof.

The figure is a view in elevation, showing my new design.

I claim:

The ornamental design for a bowl as shown.

Signed at Brooklyn, New York, the 24 day of October, 1921.

IRVING F. KLEINFIELD.
